UNITED STATES PATENT OFFICE.

HUGH PURDY, OF BELFAST, IRELAND.

TOY BUILDING BLOCK.

1,424,376.

Specification of Letters Patent. Patented Aug. 1, 1922.

Application filed March 13, 1920. Serial No. 385,575.

To all whom it may concern:

Be it known that I, HUGH PURDY, a subject of the King of Great Britain and Ireland, residing at Belfast, Ireland, have invented certain new and useful Improvements Relating to Toy Building Blocks, of which the following is a specification.

This invention relates to toy building blocks, its object being to provide improvements in connection with corner blocks.

Under my invention adjoining corner blocks are locked or keyed against horizontal displacement by a rod which passes through a vertical hole in each corner block, each corner block having also a vertical groove at one end adapted to engage with the tongue of a tongued and grooved wall block in the same vertical plane as the corner block. The vertical hole in the corner block is preferably 20 in the same plane as the vertical groove therein.

I will now describe my invention with reference to the accompanying drawings whereon:

25 Fig. 1 is an isometric view of a corner block made in accordance with the invention.

Fig. 2 is a plan view of a corner of a wall showing the corner blocks in position.

30 Fig. 3 is an elevation looking in the direction of the arrow *a* Fig. 2.

Fig. 4 is an outside view of the corner

looking in the direction of the arrow *y* Fig. 2.

Referring to the drawings:

As shown on the drawing I make each corner block *a* with a vertical hole *a*¹ therethrough, and at one end of the block I provide a vertical groove *a*² in the same plane as the vertical hole *a*¹. The corner blocks *a* are threaded on a rod *b* which prevents their displacement horizontally, and they can be connected with tongued wall blocks *c* to key same, being superimposed one above the other and arranged with their grooved ends 40 engaging the tongues *c*¹ of the wall blocks at alternate sides of the corner.

Having now fully described my invention what I claim and desire to secure by Letters Patent is:

As a new article of manufacture a toy building corner-block comprising a parallelepiped slotted at one end and having a hole therethrough in the same plane as the slot located a distance from the end equal to half the width of the block whereby the block is made available for any corner position in erecting a toy building.

In testimony whereof I affix my signature in presence of two witnesses.

HUGH PURDY.
